UNITED STATES PATENT OFFICE.

AUGUST F. KUESTER, OF CLINTONVILLE, WISCONSIN.

LIGHT-DUTY PORTABLE GRADING APPARATUS.

1,316,046.

Specification of Letters Patent. Patented Sept. 16, 1919.

Application filed May 5, 1919. Serial No. 294,900.

To all whom it may concern:

Be it known that I, AUGUST F. KUESTER, a citizen of the United States, and resident of Clintonville, in the county of Waupaca and State of Wisconsin, have invented certain new and useful Improvements in Light-Duty Portable Grading Apparatus; and I do hereby declare that the following is a full, clear, and exact description thereof.

10 The primary object of my invention is to provide a simple, economical and durable light duty power driven grading apparatus, its construction and arrangement being such that it can be handled by unskilled labor at 15 a minimum expense, while at the same time it is sufficiently elastic and adjustable to meet all excavating problems of a limited capacity ordinarily encountered.

1 I am aware that apparatus of this general type can be obtained upon the market, but the first cost of this apparatus is prohibited so far as the small contractor or user might be interested, and outside of the first cost of the equipment, the cost of installation on a small job would be such as to preclude it from use. Hence the field of the apparatus mentioned is limited, bearing in mind that it requires a corps of engineers to operate the device, besides a number of 30 unskilled laborers.

2 The object of my invention is to produce a substantial apparatus of this type which can be readily transported and set up on a job within a short time and with little expense, bearing in mind that the equipment must be sold at a reasonable figure. The essential elements of my apparatus can be purchased in open market, as the major portions of said apparatus are of standard type, 35 but it is understood that the structural features of said apparatus may be varied in accordance with the knowledge and skill of the mechanic.

3 The apparatus as shown and herein described by me has been in practical operation and has demonstrated to the satisfaction of contractors that it fills the market demand, being within a reasonable cost and its mechanism being such that it can be readily set up 40 on a job and operated by unskilled labor, these functions having been previously demonstrated by actual use.

4 The other objects of my invention are to provide:

5 An oscillatory loop cable system under control of power actuated winding drums

mounted upon a suitable truck at one end of the job and having boom supported sheaves for the cable, which cable is otherwise guided by a ground system of sheaves 60 only, whereby friction is reduced throughout;

To provide a pair of working stretches of cable trained over the supported sheaves and connected to independent drums in conjunction with a return loop cable connected to the rear end of each scraper;

To provide bed plates for the support of horizontally operated ground sheaves at the receiving end of the job;

To provide means for adjusting the line of travel of the cables from the ground sheaves to the boom supported sheaves, whereby the cut of each scraper can be varied independently without resetting the 75 general cable system;

To provide a simple means for selectively applying man power or motive power to the scrapers whereby they may be dumped when desired;

To provide means for vertically supporting the return loop cable when the latter is arranged to travel down abrupt inclines;

To provide means for anchoring the main truck and its supporting boom whereby the 85 balance of load is maintained;

To provide means for adjusting the boom supported sheaves at independent angles, to position them with the line of draft, whereby friction is reduced to a minimum 90 and bunching of the cable upon the drum is eliminated.

With these and other objects in view, which will be apparent as the description proceeds, my invention resides in the novel 95 features of construction, combination and arrangement of parts as hereinafter described and defined by the appended claims, it being understood that changes in the precise embodiment might be made by those 100 skilled in the art without departing from the spirit of the invention.

In the accompanying drawings:

Figure 1 represents an enlarged detail side elevation of a truck, embodying certain features of my invention, particularly boom carrying table suspension sheaves.

Fig. 2 is a detailed end elevation of the upper portion of the truck boom showing the arrangement for adjusting the sheave.

Fig. 3 is an enlarged detailed elevation of a scraper embodying the features of my in-

vention, with parts broken away and in section to more clearly illustrate structural features, the scraper being shown with cable connections and positioned at the receiving end of a grading job.

Fig. 4 is a plan view of the same.

Fig. 5 is a diagrammatic plan view, illustrating a grading job with the truck and its associated apparatus mounted for work.

10 Fig. 6 is a sectional elevation of the apparatus corresponding to the diagrammatic view, and

Fig. 7 represents a cross-section of the job in diagram, showing variations in the 15 grade taken at points indicated by the lines *a*, *a*, *b*, *b* and *c*, *c* of Fig. 6.

Referring by characters to the drawings, 1 represents a portable truck provided with the usual frame, upon which is mounted an 20 engine or motor 2, that is connected by gears in any suitable manner to a pair of cable winding drums 3, 3', the frame of the truck has mounted thereon at one end a boom 4, which boom is suitably secured to the frame 25 of the truck and is also provided with an adjustable leg 4' which is designed to be fitted to the ground, whereby the tilting strains of the truck coincident to power being applied to the system is overcome.

30 Adjacent the upper end of the boom 4 is secured a pair of notched cross bars 5' which bars are adapted to support hangers 7, 7' of a pair of cable supporting sheaves 8, 8'.

By referring to the diagrammatic view, 35 Fig. 5, it will be seen that under certain conditions, the cable stretches will travel at an angle to its respective drum, and in order to prevent "bunching" of the cable upon its winding drum, the sheaves may be adjusted transversely into any one of the 40 notches of the bars 5', so as to compensate, to a certain degree, for the angularity of the cable. As, for example in Fig. 5, the sheave 8 is shifted to its extreme position at one 45 side of the boom, due to the fact that its cable, as shown in the diagram, is drawing at a comparatively greater angle than the companion cable.

Connected to the drum 3, is one end of a 50 working cable 9, the same being trained over the supporting sheave 8' and from thence it is directly connected to the front end of a suitable scraper A. A similar working cable 9' has one end connected to the drum 3' and 55 is trained over the supporting sheave 8, being connected to the front end of a second scraper B.

A return cable loop 10 has one end connected to the rear portion of the scraper B 60 and its other end correspondingly connected to the rear portion of the scraper A. This cable is trained over a pair of ground sheaves 11, 11' which are mounted upon plates 12, 12' that are anchored to the ground beyond 65 the operative field of the scrapers, at the re-

ceiving end of the job. The area of the grading job is indicated by the dot and dash lines *x*, *x*, *x*', *x*'', the lines *x*', *x*'' showing the delivery and receiving ends of the job respectively, while the lines *x*, *x* indicate the 70 width of the job.

In order to provide a simple means for anchoring the ground sheaves, which operate horizontally, I provide bed plates 12, as best shown in Fig. 4, which plates have a 75 series of apertures 13. The apertures are adapted to receive stakes 13' that are driven into the ground, as plainly indicated in Fig. 3. In setting up for a grading job, after these plates have once been anchored, it is 80 not ordinarily necessary to shift the ground sheaves, which would necessitate more or less complications and loss of time, and to overcome this shifting of the ground sheaves at frequent intervals, I provide adjustable 85 floating guide pulleys 14 as indicated in the diagram and best shown in detail in Fig. 3 of the drawings. These guide pulleys are of comparatively light construction and they embody as shown, ordinary block and tackle 90 construction embodying outer and inner pulleys 15, 15' respectively, which pulleys have trained thereover an adjustable line 16 which may be adjusted to vary the length of the device as a whole, it being understood 95 that the inner block 15' is secured in any suitable manner to an anchor stake 17, and these anchor stakes can be selectively placed as desired, between the ground sheaves 11, 11' and the working field of the job, which is 100 indicated by the dotted line *x*''. It is obvious that any suitable adjustable pulley construction may be used as a substitute for the block and tackle just described, the essential feature being the guide pulley 14, 105 and some means for anchoring and adjusting it with relation to its anchor, whereby the longitudinal stretches of the cable loop 10 can be shifted from their angle points controlled by the ground sheaves. By shifting these cable stretches 10, 10 horizontally, 110 it will be manifest that the line of draft of the scrapers can be selectively changed as the work progresses, so as to avoid frequent changes in the position of the main truck 115 and ground sheaves at their respective ends of the job.

Referring now more particularly to Fig. 3, it will be observed that one of the ground pulleys 14 is shown in detail and in its position it can be utilized not only to deflect the cable 10 horizontally, but it is utilized also for the purpose of effecting a clearance of this cable stretch at a high point of the ground, at which point the cable, due to 120 the weight of the scraper and its load, will deflect downwardly, this incline of the ground at the receiving end of the job being in proportion to the depth of the excavation.

As best shown in Figs. 3 and 4, the re- 130

ciprocative scraper units embody a standard scoop pan 18 having suitable braces and a controlling bar 19 projecting from its rear or dump wall. When the pan is used for 5 working in hard soil or clay, I provide its front cutting edge with a series of teeth 18' but in sand or soft soil, these teeth may be dispensed with. The working stretch of cable 9 is connected to the front portion of 10 the scraper by suitable bail 20, the arms 21 of which, are pivotally united with the sides of the scoop by means of loops 21', which loops are located comparatively close to the bottom of the pan and a second pair of 15 loops 22 are located above the same to form a connection for a return bail 23, which bail is similar in construction to the front bail previously mentioned.

In order to provide a power dump for the 20 scraper, in addition to the hand dump bar 19, I have shown a dumping coupling 24 which comprises a short stretch of chain, having one end connected to the upper portion of the rear wall of the scoop, its opposite end 25 being provided with a hook 24'. When this coupling is not in use, it may rest loosely in the pan, and when it is desired to dump by power, the working stretches of the cable 9 is slackened from the drum 3', and the 30 dumping coupling as shown in dotted lines in Fig. 3 is connected to a ring 25 by means of the hook 24'. When pull power is imparted to the cable 9, it will be apparent that the load strain will be transferred from the 35 pulling bail 20 to the upper central portion of the pan back wall. Hence this change of levers will cause the load to automatically dump, while the cutting teeth 18 will act as a fulcrum point upon which the pan will 40 rock forward. To return the pan to its normal scraping position after dumping, by imparting a reverse pull upon the scraper through the return cable loop 10, working stretches 9' and power driven drum 3', it 45 will be seen that the scraper will respond quickly and return to its normal position. This reverse action of the scraper is assured, due to the leverage between the points of connection of the bails 20 and 23 with the 50 sides of the pan as previously mentioned.

From the foregoing description it will be manifest that with this apparatus, it will only require one man upon the main truck for manipulating the drums 3 and 3' and 55 one man in the field for controlling the moment of dump of the scrapers. It will be observed that the working stretches 9 and 9' of the cable system will pull directly from the load over the suspension sheaves 60 which are carried by the boom truck and thus all drag of the working cables is eliminated, when the scrapers are operating under load conditions, whereby wear and friction are reduced to a minimum. This reduction 65 of friction is further taken care of by rea-

son of the fact that the cables when operating under load conditions or otherwise, will pull approximately in alinement with the main truck supporting sheaves and the permanently anchored ground sheaves, 70 whereby all unnecessary angles are avoided and the power of the motor is utilized as direct as possible. This condition being also true when the return loop 10 of the cable system is deflected from its permanent guard 75 point about either one of the ground sheaves 11 and 11'.

While I have shown the return loop 10 of the cable system in dotted lines, deflected inwardly from its full line position, it is 80 apparent that the floating guide pulleys may be staked upon the opposite or outside of the area of the job, as indicated at α whereby the scope of adjustment of said cable system may be increased proportionately. 85

As best shown in the diagrammatic view in Fig. 6, the soil indicated at y is to be removed to a depth as indicated by the dotted lines y' and with this in view the scrapers are manipulated to pull the desired number of cubic feet of this soil down to the point indicated at a , a , which is a low point, whereby the removed soil can be utilized to bring the low point up to the grade lines y' . 95

Obviously it will be seen that by adjusting the guide pulleys 14, any grade can be completed by displacement of the soil from a selected line of draft toward the power truck, and when one longitudinal portion of 100 the job is completed, the truck may be moved, for example, to a central position, with reference to the width of said job, and after the scrapers are manipulated at this position to their limit of economy, the truck 105 is moved to the dotted position indicated at α in Fig. 5, and the operation of grading is then repeated, bearing in mind that the guide pulleys 14 are the only elements which are moved constantly to adjust same to vary 110 the cut.

I am also aware of the fact that various 115 grading apparatus have been used wherein the cables are suspended in the form of a trolley system, but this type of apparatus is expensive and requires a large volume of work for installation, as well as requiring the major portion of the system to be knocked down and remounted after the scrapers have been operating a short time. 120 This type of scraping cable system is therefore impractical for the purposes to which my invention is applied, as it is essential that a small single loop system be employed which can be readily adjusted to cover all 125 the conditions of small grading jobs, and with the system as I have described, this result is obtained.

What is claimed is:

1. In a light duty grading apparatus, a 130

portable motor carrying truck adapted to be located at the discharge end of a grading job and to be intermittently shifted transversely as the work progresses, the truck being provided with motor driven cable systems, a boom, and a pair of suspension cable sheaves carried by the boom; the combination of a reciprocated working stretch of cable carried by each drum and trained over one of the suspension sheaves, a pair of reciprocated pull scrapers each having its front portion connected to the end of each working stretch of cable, a return cable loop having its ends connected to the rear portion of each scraper, ground horizontally disposed sheaves adapted to be anchored at the receiving end of the grading job and spaced transversely thereof over which the return cable loop is trained intermediate of its ends, and adjustable guide pulleys for the return cable loops located between the ground sheaves and reciprocated scrapers for varying the line of travel of the working stretch of the cable system relative to the ground sheaves and boom carrying supporting sheaves.

2. In a light duty grading apparatus, a

portable motor carrying truck adapted to be located at the discharge end of a grading job and to be intermittently shifted transversely as the work progresses, the truck being provided with motor driven cable system, a boom, and a pair of suspension cable sheaves carried by the boom; the combination of a reciprocated working stretch of cable carried by each drum and trained over one of the suspension sheaves, a pair of reciprocated pull scrapers each having its front portion connected to the end of each working stretch of cable, a return cable loop having its ends connected to the rear portion of each scraper, bed plates adapted to be anchored to the ground at the receiving end of the grading job, horizontally disposed ground sheaves mounted thereon over which the return cable loop is trained intermediate of its ends, and adjustable guide pulleys for the return cable loops.

In testimony that I claim the foregoing I have hereunto set my hand at Milwaukee, in the county of Milwaukee and State of Wisconsin.

AUGUST F. KUESTER.
